UNITED STATES PATENT OFFICE

2,404,315

RECIPROCATING ENGINE

Lutwin C. Rotter, Maplewood, and Victor G. Klein, St. Louis, Mo., assignors to Lincoln Engineering Company, St. Louis, Mo., a corporation of Missouri

Original application October 4, 1943, Serial No. 504,852. Divided and this application December 11, 1944, Serial No. 567,590

5 Claims. (Cl. 74—100)

1

This invention relates to engines, and with regard to certain more specific features to reciprocating air engines for driving lubricant pumps and the like.

This invention is a division of the invention specified in our United States patent application Serial No. 504,852, filed October 4, 1943, for Reciprocating engine.

Among the several objects of the invention may be noted the provision of a compactly formed lost-motion coupling between the main reciprocating parts of an engine and its valve gear whereby with a fewer number of parts the valve gear may be located so as to effect better distribution of air to the engine cylinder; the provision of an apparatus of the class described which allows of a better distribution of wear between the engine piston and its cylinder; and the provision of a simplified longer wearing engine valve gear. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a side elevation of an engine embodying the invention;

Fig. 2 is a cross section taken on line 2—2 of Fig. 1, parts being shown in elevation;

Fig. 3 is a section taken on line 3—3 of Fig. 2;

Fig. 4 is an enlarged vertical section taken on line 4—4 of Fig. 2 showing certain parts over-centered upward; and,

Fig. 5 is an enlarged horizontal section taken on line 5—5 of Fig. 4 but showing parts in dead-center position.

Similar reference characters indicate corresponding parts throughout the several views of the drawings.

In United States Patents 2,215,852 and 2,269,423, dated September 24, 1940, and January 13, 1942, respectively, are shown valve mechanisms and the air engines which they serve, upon which the present invention is an improvement. The present invention is an improvement of that type of valve gear and upon the location of it on the air engine cylinder. Instead of being at the end as in said patents, the valve gear is on the side of the cylinder. The valve gear itself is improved by providing a better straight-line trip-shoe ac-

2

tion which decreases wear and lengthens life. The invention also provides an improved valve driving mechanism. The invention permits the use of shorter air distribution passages with consequent higher capacity. In addition it eliminates the coaxial lost-motion mechanisms shown in said patents. Instead of said coaxial lost-motion mechanisms, a laterally located lost-motion mechanism is arranged which however, unlike former laterally located mechanisms of this type, allows for a free piston rotation. This reduces engine cylinder and pump plunger wear.

Referring now more particularly to the drawings, numeral 1 indicates the cylinder of the engine, numeral 3 is the piston on the piston rod 5, the latter passing through a packing gland 1. A cylindric frame 9 connects the cylinder 1 with the pump 11. The rod 5 is directly connected to the rod 12 of the pump 11 for direct-connected reciprocating driving purposes. The cylindric frame 9 is cut away as shown at 10 for access to parts to be described. Other parts are extended as shown at 23 to form a box-like enclosure for a linkage to be described.

One side of the cylinder 1 is provided, as indicated at numerals 13 and 15, with inlet and exhaust ports with which a D-valve 17 cooperates. In cover 19 is the valve gear per se. The operating stem of the valve is shown at 21. This stem 21 passes through a reciprocating gland 51 and is located at its opposite end in a bearing 53. In the bearing 53 the stem carries a sleeve 55 attached to it by means of a pin 57. This forms a shoulder 63 for purposes which will appear.

Sliding on a reduced section 59 of stem 21 is a trip shoe 61. By reason of the upper shoulder 63 formed by a sleeve 55, and a lower shoulder 65, the stem 21 has lost-motion engagement with respect to the trip shoe 61 whether the shoe be up or down. The trip shoe has end shoulders 67 and 69 which provide lost-motion engagement between the shoe and the D-valve 17.

Extending from the trip shoe 61 is a pin 71 which reaches through a fork or clevis 73 of a rocker 75. Within the clevis the pin 71 carries a roller 77. The roller 77 rolls on a vertical guide surface 78 which forms part of a U-shaped member 79 bolted to the cover 19 as indicated at 81. Guides are formed by the edges 83 of the member 79 and by a shoulder 85 of the cover 19. These guides are for a sliding yoke 87 which is pivoted at 89 to an air-tight plunger 91. The plunger operates in a stuffing box 93 and carries an exteriorly extending tell-tale 95.

The rocker 75 is supported by (and slides in)

a fork 97 which has a pivot 99 in a bearing 101 of the case 19. Beyond the fork 97 the rocker 75 is made as a fork or clevis 103 for receiving a second roller 105. The clevis has extended ends 107 movably engaging opposite faces of the adjacent portion of the yoke 87. This guides the rocker co-planar with the yoke.

The roller 105 contacts a driven face 109 of the yoke 87 which although movable is at all times parallel with face 78. Face 78 is turned into the plane of the yoke (Figs. 4 and 5). Thus if the rocker is moved counterclockwise (Fig. 4) the roller 77 will traverse face 78 and roller 105 will traverse face 109, thus driving the yoke 87 to the right. This pulls in the plunger 91. The plunger is biased outward by air pressure carried within the cover 19. This pressure is supplied by the air admitted from inlet opening 111 and which passes to the port 13 via the D-valve 17 which effects its proper distribution. Thus it will be seen that the yoke 87 is normally biased to the left (Fig. 4) by the air pressure tending to push out the plunger 91. When the rocker 75 rotates counterclockwise, the yoke is pushed to the right. The yoke reaches its maximum position toward the right when the rocker 75 is about horizontal (see Fig. 5). This is the dead-center position. Thereafter further movement of the rocker will cause the yoke to urge it further in a counterclockwise direction. Down to the dead-center position, the descending rod 21 is responsible for drawing down the pin 71, through cooperation between the shoulders 63 and 69.

Movement to dead-center position about takes up the lost-motion between the trip shoe 61 and the D-valve 17. Then upon over-centering, the leftward bias of the yoke 87 (from plunger 91) urges the rocker 75 further counterclockwise. At this time the distance between shoulders 67 and 65 is traversed. Downward motion of pin 71 being at this time unimpeded. This drives down the pin 71, trip shoe 61 and D-valve 17. Thus the lost motion between shoulders 67 and 65 is taken up after overcentering. The air pressure in the cover 19 tending to force the plunger 91 out of the gland 93 causes the bias. Hence the D-valve 17 is reset to introduce air above the piston 3 when the piston has about reached its dotted line position shown in Fig. 2. This reverses the piston movement, and through the valve driving mechanism (to be described) ultimately reverses the movement of the stem 21 whereupon the above described action between stem 21 and shoe 61 is repeated in reverse. The only difference is that this time the lost-motion between the trip shoe 61 and the D-valve 17 is below the valve, and the lost-motion between the trip shoe and the stem 61 exists above between shoulders 69 and 63. In this case initial movement of the rocker 75 to dead-center position is clockwise. This again forces the yoke 87 to the right until dead-center is reached, whereupon bias of the yoke forces the rocker further clockwise so that snap-action occurs back to the position shown in Fig. 4, thus resetting the valve to the position shown in Fig. 2. Upward movement again introduces clearance between lower shoulders 67 and 65 on the one hand and contact between upper shoulders 63 and 69 on the other hand, the latter being necessary for the subsequent downward operation.

This valve gear has the substantial advantage over those shown in said Patent 2,269,423 in that there is no lateral rocking movement required of the pin 71 which in the present case simply translates in a straight line. This allows for arranging

better bearing surfaces for the parts connected with the pin 71 and a longer life. The device is simpler and easier to manufacture than that shown in said Patent 2,215,852.

The stem 21 reaches into the enclosure 23, and underneath a removable cover 14 through an opening 16. In the enclosure is a pivot 25 for a rocker 27. Pivot 25 is held in bearings 26. At the left (Fig. 2) the rocker 27 is pivoted at a clevis 28 with a connecting link 29 (see pivot 31). The connecting link 29 is pivoted at 32 in a clevis 35 attached to the rod 21 by threading and a cotter key 36.

On the right-hand side, the rocker 27 is forked as indicated at 37 providing spaced fingers 39. Pressed into each finger 39 of the fork 37 is a rounded hardened wear pin 41. Operating between the pins 41 is a driving disc 43. Disc 43 is welded to the piston rod 5. The frame 9 and the enclosure 23 are designed to fit closely around the described linkage, including the disc 43, except at opening 10 which is to permit access.

Operation not already described is as follows: Upon reciprocation, the disc 43 strikes first one pin 41 (solid lines, Fig. 2), and then the other (dotted lines), with lost motions therebetween. The lost motion is of a degree adapted to produce valve over-centering snap action only whenever the piston 3 is near the end of its stroke (see dotted lines in Fig. 2), thus making the engine 1 of the so-called full-stroke type. That is, there is no cut-off expansive event in the work cycle of the engine cylinder.

Another advantage of the invention is that the connection between the rocker 27 and the disc 43 is such that the disc may rotate freely along with the piston 3 which is in the cylinder 1, and also the piston rod 5 in the packing 7, as well as the plunger 12 of the pump 11 in its cylinder. Thus scoring and localized wear is reduced in these parts. In other words, the reciprocating parts may rotate indifferently instead of being confined to pure axial movement. In addition, the valve gear is placed closer to the point of air delivery in the cylinder 1, and therefore, the passages 13 and 15 become much shorter. Consequently less friction restricts flow of air and capacity is increased. At the same time the operating parts are compactly arranged in a space which is closely surrounded by guarding frame portions which form the connection needed between the engine and pump parts.

It will be noted that the connecting parts 9 between the engine and pump forms a cylinder closely surrounding the cylindric figure swept out in space by the reciprocating disc 43.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. Over-centering valve mechanism comprising a fixed guide, a movable guide moving laterally thereto, means for biasing the movable guide toward the fixed guide, a rocker carrying near one end means engaging and movable along the fixed guide and at the other end means engageable with and movable along the movable guide, pivoting means supporting said rocker for 70 rotary and relative sliding movement, and a re-

ciprocating trip shoe pivotally attached near one end of said rocker and movable along a line between the fixed guide and said pivoting means.

2. Over-centering valve mechanism comprising a straight fixed guide, a straight movable guide parallel thereto, means for biasing the movable guide at right angles toward the fixed guide, a rocker carrying near one end means engaging and movable along the fixed guide and at the other end means engageable and movable with the movable guide, pivoting means supporting said rocker for rotary and relative sliding movement, and a reciprocating trip shoe pivotally attached near one end of said rocker and movable along a straight line parallel to the fixed guide and between it and said pivoting means.

3. Over-centering valve mechanism comprising a straight fixed guide, a straight movable guide parallel thereto, means for biasing the movable guide at right angles toward the fixed guide, a rocker carrying near one end means engaging and movable along the fixed guide and at the other end means engageable and movable with the movable guide, pivoting means supporting said rocker for rotary and relative sliding movement, and a reciprocating trip shoe pivotally attached near one end of said rocker and movable along a straight line parallel to the fixed guide and between it and said pivoting means, said rocker and the engagement regions on the guides being in the same plane.

4. Snap-acting valve mechanism comprising a yoke, a yoke guide carrying said yoke for reciprocating movement, a fixed guide located inside of the yoke and in its plane of movement, said second guide being at an angle to the first-

mentioned guide, a rocker forked at both ends and located within said yoke in the plane of said fixed guide, a roller and a trip shoe pivoted in the fork of the rocker adjacent to said fixed guide and movable in a direction to cause said roller to traverse said fixed guide, a roller in the fork at the other end of the rocker, a pivoting support for the rocker restraining it to rotate with the pivoted means and to slide with respect to the same during rotation, said yoke having a driven surface engaged by said second-mentioned roller in the plane of the first-mentioned roller and the said fixed guide.

5. Snap-acting valve mechanism comprising a yoke, a guide carrying said yoke for reciprocating movement, a second guide located inside of the yoke and in its plane of movement, said second guide being at an angle to the first-mentioned guide, a rocker forked at both ends and located within said yoke, a roller and a trip shoe pivoted in the fork of the rocker adjacent to said second guide and movable in a direction to cause said roller to traverse said second guide, a roller in the clevis at the other end of the rocker, a pivoting support means for the rocker restraining it to rotate with the pivoting means and to traverse the same during rotation, said yoke having a driven surface engaged by said second-mentioned roller in the plane of the first-mentioned roller, and means biasing the yoke in a direction tending to force the rocker through the pivot means and toward said second-mentioned guide, said last-named means comprising an air operated plunger attached to the yoke.
